UNITED STATES PATENT OFFICE.

CHARLES F. CLAWSON, OF MOUNT PLEASANT, IOWA.

RAIL-ANCHOR.

972,061.

Specification of Letters Patent.

Patented Oct. 4, 1910.

Application filed June 20, 1910. Serial No. 567,918.

To all whom it may concern:

Be it known that I, CHARLES F. CLAWSON, a citizen of the United States, residing at Mount Pleasant, in the county of Henry and State of Iowa, have invented certain new and useful Improvements in Rail-Anchors; and I do declare the following to be a full, clear, and exact description of the invention, such as will enable others skilled in the art 10 to which it appertains to make and use the same.

This invention relates to improvements in anchors for railway rails.

The object of the invention is to improve 15 the construction of the anchor shown in my application Serial No. 548,381 filed March 10, 1910, whereby the two sections of the anchor will be more securely held together.

With the foregoing and other objects in 20 view the invention consists of certain novel features of construction, combination and arrangement of parts, as will be more fully described and particularly pointed out in the appended claims.

25 In the accompanying drawings: Figure 1 is a plan view of my improved anchor showing the same applied to a rail tie; the rail being shown in dotted lines; Fig. 2 is a plan view of the parts removed from the rail and 30 separated; Fig. 3 is a side view of the anchor; Fig. 4 is an end view thereof; and, Fig. 5 is a vertical longitudinal section on the line 5—5 of Fig. 4.

Referring more particularly to the drawings 35 1 denotes the rail and tie engaging member of the anchor and 2 denotes the rail engaging or gripping member thereof which has a sliding engagement with the tie engaging member as will be hereinafter more 40 fully described. On the outer sides of the members 1 and 2 are formed flange engaging clips 3 which are adapted to engage and fit around the opposite edges of the base flanges of the rail as shown. The clips 3 are 45 preferably reinforced by integral bracing ribs 4.

On the forward end of the tie member 1 of the anchor near its inner edge is formed a downwardly projecting stop lug 5 which is 50 preferably curved outwardly to a slight extent at its lower end as shown. The lug 5 is preferably reinforced on its rear side by integral reinforcing ribs 6. When the anchor is 55 in position on the rail the lug 5 will engage the side of a tie thus forming a stop or anchor for the rail.

In order to cause the two sections or members of the anchor to automatically grip the flanges of the rail and to hold said sections or members in operative engagement with each other I form the meeting edges of said members on an angle as clearly shown in Figs. 1 and 2 of the drawings and on the lower side of the inner edge of the member 1 is formed a downwardly projecting extension or enlargement 7 which extends parallel or in line with the angular or oblique inner edge of the member and has formed therein a rabbeted passage or groove 8. The passage or groove 8 is also in line with the angular inner edge of the member as shown. On the free edge of the projection or enlargement 7 is formed a toothed or corrugated surface 9 the purpose of which will hereinafter be described.

The inner or meeting edge of the rail engaging member 2 is formed on an angle corresponding to the angle of the inner edge of the member 1 and on the lower side of the inner edge of the member 2 is formed a 80 downwardly projecting tongue 10 having its inner edge projecting laterally beyond the inner edge of the member 2 to form a bead or rib 11 which projects into the rabbeted portion of the groove 8 of the member 1 85 when the tongue 10 is engaged therewith thereby forming an interlocking engagement or connection between the inner edges of the two members of the anchor whereby said members are prevented from becoming 90 casually separated and are held in tight engagement with the bottom of the rail. On the lower surface of the member 2 adjacent to the outer edge of the tongue 10 is formed a series of teeth or corrugations 12 which are 95 adapted to be engaged by the teeth or corrugated surface of the inner edge of the enlargement 7 of the member 1 whereby the frictional engagement between the two members is increased.

In the operation of the device the rail or tie engaging member 1 is placed in position on the rail with the stop lug 5 in engagement with the side of a tie after which the member 2 is engaged with the rail and the tongue 10 of said member engaged with the groove 8 in the member 1. With the parts thus engaged the member 2 is driven into place by tapping the outer end thereof with a hammer or similar implement thus causing 110 the clips on the outer side of the member to firmly grip the flanges of the rail. When

thus driven into place the corrugated or toothed engaging surfaces of the two members will prevent the member 2 from slipping back on the member 1. The interlocking connection between the engaging edges of the anchor members prevents any possibility of their casually becoming separated.

While I have shown and described my invention in the form of a rail anchor it is 10 obvious that the same may be constructed in the form of a tie plate anchor.

From the foregoing description taken in connection with the accompanying drawings, the construction and operation of the invention 15 will be readily understood without requiring a more extended explanation.

Various changes in the form, proportion and the minor details of construction may be resorted to without departing from the 20 principle or sacrificing any of the advantages of this invention as defined in the appended claims.

Having thus described my invention, what I claim is:

25 1. A rail anchor comprising a rail and tie engaging member having formed therein adjacent to its inner edge a rabbeted groove, a tie engaging lug formed on one end of said member, a rail engaging member adapted to 30 coact with the tie member whereby said

members are adapted to firmly grip a rail and a tongue formed on the inner edge of said rail member said tongue having a projecting rib adapted to engage the rabbeted portion of the groove in the tie member 35 whereby an interlocking connection is had between said members.

2. In a rail anchor a rail and tie engaging member having formed on its inner edge a downwardly extending enlargement provided with a longitudinally disposed rabbeted groove, a corrugated bearing surface formed on the inner edge of said enlargement, a rail engaging member having on its lower side a corrugated surface adapted to 45 engage the corrugated surface on the enlargement of the tie member and a tongue formed on the inner edge of said rail member, said tongue having a rib adapted to engage the rabbeted portion of the groove in 50 the tie member whereby said members have interlocking connection.

In testimony whereof I have hereunto set my hand in presence of two subscribing witnesses.

CHARLES F. CLAWSON.
